UNITED STATES PATENT OFFICE.

MARCEL AIMON, OF PARIS, FRANCE.

BINDING FOR STITCHED BOOKS.

Application filed February 4, 1927; Serial No. 165,953, and in France February 6, 1926.

This invention relates to a binding for books which is strong and handy, designed to be applied instantaneously upon stitched volumes of all kinds to which it gives the 5 appearance of bound books suitable to be placed in a book-case.

The binding according to the present invention comprises essentially two rigid double panels constituting the sides through 10 which passes a connecting part forming the back of the book which is made slidable in order to allow of inserting stitched books of various thicknesses. The back is also preferably provided with an opening to allow 15 reading of the title and the author's name. The book is retained in its cover by means of slidable hooks placed on the edges in the interior of the panels. It will be evident that the present system of binding allows of 20 assembling together in the same cover several pamphlets or even loose sheets.

In the case of pamphlets they are provided with longitudinal wires inserted between the sheets and provided at both ends with heads 25 of appropriate shape which are retained side by side in transverse guides secured on both sides by means of the hooks already mentioned.

In the case of loose sheets the latter are 30 assembled by means of special clips provided with guides allowing the fixation on wires similar to those of the pamphlets. In this manner sections and loose sheets of all kinds may be assembled in the same cover by the 35 same devices.

The present system allows also to place on both sides of bound books loose sheets retained in position by the covers and designed to be used for various purposes such as 40 advertisements, notes, etc.

The appended drawings illustrate as examples various manners of execution of the improved binding, object of the invention, in different cases, viz.; a complete book, sections, 45 loose sheets.

Figs. 1 to 6 show the arrangement used for complete works of different thickness.

Fig. 1 is a front view of same in the open position seen from the interior.

Fig. 2 is a sectional view on line 2-2, Fig. 1.

Fig. 3 is a part section on line 3-3, Fig. 1.

Fig. 4 is a diagrammatic view in section 55 of the closed binding with loose sheets, the book itself being omitted.

Fig. 5 is a front view of the inner connecting part for the sides.

Fig. 6 is a front elevation showing by 60 way of example a loose sheet.

Figs. 7 to 15 show the binding of pamphlets and loose sheets.

Fig. 7 shows the binding in the open position the pamphlets being omitted.

Fig. 8 shows the binding in the open position with the pamphlets in engagement.

Fig. 9 is an enlarged view of the metallic binding system.

Fig. 10 is a vertical sectional view of same.

Fig. 11 is a horizontal sectional view on 70 line 11-11, Fig. 9.

Fig. 12 is a transverse sectional view of a pamphlet provided with its suspending wire.

Fig. 13 is an enlarged view showing the 75 locking device for the guides.

Fig. 14 is a side elevation of the special clips for sheets mounted on a wire.

Fig. 15 is a sectional view of a wire on line 15-15 of Fig. 14.

As will be seen in Figs. 1 to 6 the sides 80 or covers of the binding are constituted by double rectangular panels of strong cardboard for example *a*, *a'*, *b*, *b'*, the outer panels *a'*, *b'* being suitably decorated. For each side the panels *a*, *a'* and *b*, *b'* are kept 85 apart for instance by means of two cardboard triangular pieces *c* leaving the longitudinal sides open between said pieces and the parts are assembled together by means of bands *d* and corner pieces *e* fixed by an adhesive material. The interior panels *a*, *b* are each provided with two paper or linen pieces *f* glued upon them and forming sleeves or sockets in which pins *g* are slidably mounted. The inner end of each pin is bent to form a 90 short lug *g'* while the outer end has a relatively long hook *g''* formed by bending the pin back onto itself.

The two sides *a*, *a'*, *b*, *b'* are assembled together by means of a part *h*, as will be 100 seen in Fig. 5, which passes into the space left between the panels and is afterwards folded onto both sides as at *h'* shown in Figs. 1, 7 and 8. The part *h* is provided in its middle portion which forms the back of 105 the book cover with an opening *i* to show the title of the book and the author's name.

As shown in Fig. 6, a loose sheet *j* is provided with a lateral tongue *j'*, preferably made integral therewith and adapted to be 110 introduced into the space formed between each pair of panels. There may be any num-

ber of such sheets and they are utilized for different purposes such as advertising, for notes, etc.

It will be understood that in order to give a good appearance to the whole the material employed for making the corners *e*, the bands *d* and the back *h* will be preferably identical. Likewise the fold of the loose sheets *j* which is seen in part through the opening *i* will have preferably the same appearance as the back *h*.

The mode of operation of the binding made in the manner thus described is as follows. Assuming the hooks *g*² to be in the position shown in Fig. 1, the stitched book is placed on edge and a few back and front leaves respectively are folded back and caught at the top and the bottom by pushing in the hooks causing the pins *g* to slide in the sleeves *f*. The connecting part *h* is then drawn tight, care being taken to place the opening *i* in the middle, when the ends *h*¹ are folded back the binding is completed.

In the case where several pamphlets are to be bound together, the same covers may be used but the hooks *g*² of the pins *g* can then enter a movable metal guide *k*, seen in Fig. 7, which determines the width of the back of the cover. There is one of these metal guides at each end, which are preferably of T-shape interiorly in order to allow introducing endwise wires *l* provided with a flat head *m* preferably of cylindrical shape upon which the pamphlets *n* to be bound are simply folded as will be seen in Fig. 12. The outer side *k*¹ of each guide *k*, has an aperture *k*² near each end to receive the hooks *g*² of the wires *g*, as shown in Figs. 9 and 13. The back of the guide extends beyond the sides as shown at *k*³ to insure the rigidity of the back while the pins *g* and hooks *g*² operate as hinges and lie in the plane of the pins *l* as shown in Fig. 11.

The guides *k* are preferably secured in place by means of small collars, (Fig. 13) which have a portion *r* of substantially the same shape in cross section to the cross-section of the guides and an extended flange *r*¹ by means of which the collars may be riveted to the back portion *h*.

It will easily be seen that in order to bind together several pamphlets previously provided with wires it will be sufficient to engage the top ends of the latter in the guides *k*, and then connect the guides to the back *h* by causing said guides *k* to enter the collars *r* and finally to lock the four hooks *g*² in the guides *k*. In order to prevent the wear and tear by friction of lugs *g*¹ they may be covered over by two flexible flaps *o* secured in the middle of the panels, as will be seen in Figs. 7 and 8.

The binding of loose sheets will be effected by means of spring clips *p* simply formed by stamping for instance in a sheet

of metal and subsequently bent so as to form when folded a cylindrical hinge *q* for engagement upon the wires *l*, the length of said hinges being greater than the width of the clips in order to avoid the tearing of the leaves when the clips are put in juxtaposition. The front half *p*¹ of the clip will preferably be shorter than its back half *p*² the edge of which will be slightly folded back in order to ensure a better hold upon the leaves. It is evident that the clips *p* may be covered over with any appropriate metal coating such as nickel, silver, etc., and be provided with signs for classifying such as the letters of the alphabet. 80

Having now described my invention I declare that what I claim and desire to secure by Letters Patent of the United States is:—

1. A book and leaf binder comprising side members each formed of superposed panels, spacing members interposed between the panels and forming transverse spaces between the latter opening at the longitudinal edges of the panels, and a back forming member extending longitudinally between said side members and having lateral portions extending through said transverse spaces, the free ends of the lateral portions adapted to be folded onto and secured to the inner panels. 85

2. A book and leaf binder comprising side members each formed of superposed panels, triangular spacing pieces interposed between the panels at the upper and lower edges thereof and forming a transverse space between the panels, said space converging from the inner to the outer edges of the panels and a back forming member extending longitudinally between the inner longitudinal edges of the side members, said back forming member having lateral converging portions extending through the transverse spaces, the free ends of the lateral portions being folded over and secured to the inner panels of the side members. 100

3. A book and leaf binder comprising side members each formed of superposed panels, triangular spacing pieces interposed between the panels at the upper and lower edges thereof and forming a transverse space between the panels said space converging from the inner to the outer edges of the panel, a back forming member extending longitudinally between the inner longitudinal edges of the side members, said back forming member having lateral converging portions extending through the transverse spaces, the free ends of the lateral portions being folded over and secured to the inner panels of the side members, and means at the corners of the superposed panels for connecting them together. 115

4. A book and leaf binder comprising side members, each formed of superposed panels, 130

spacing members interposed between the panels and forming transverse spaces between the latter opening at the longitudinal edges of the panels, a back forming member 5 extending longitudinally between the side members and having lateral portions extending through said transverse spaces and connected at their outer ends to the inner panels, and pins slidably mounted adjacent the inner 10 longitudinal edges of the side members having hooks formed on their outer ends for engaging leaves interposed between the side members.

5. A book and leaf binder comprising side 15 members each formed of superposed panels, spacing members interposed between the panels and forming transverse spaces between the latter opening at the longitudinal edges of the panels, a back forming member 20 extending longitudinally between the side members and having lateral portions extending through said transverse spaces and connected at their outer ends to the inner panels, sleeves mounted on the inner panels 25 adjacent the back forming member, and pins slidably mounted in the sleeves and having hooks formed on their outer ends.

6. A book and leaf binder comprising side 30 members each formed of superposed panels, spacing members interposed between the panels and forming transverse spaces between the latter opening at the longitudinal edges of the panels, a back forming member 35 extending longitudinally between the side members and having lateral portions extending through said transverse spaces and connected at their outer ends to the inner panels, sleeves mounted on the inner panels adjacent the back forming members, pins 40 slidably mounted in the sleeves and having hooks formed on their outer ends, hollow transverse guide members secured to the back forming members at the upper and lower edges of the latter and a series of leaf-holding 45 wires slidably mounted in the guide members and extending longitudinally of the back-forming member.

7. A book and leaf binder comprising side members each formed of superposed panels, spacing members interposed between the 50 panels and forming transverse spaces between the latter opening at the longitudinal edges of the panels, a back-forming member extending longitudinally between the side members and having lateral portions 55 extending through said transverse spaces and connected at their outer ends to the inner panels, sleeves mounted on the inner panels adjacent the back forming member, pins slidably mounted in the sleeves and having 60 hooks formed on their outer ends, hollow transverse guide members having an interior T-shape in cross section, secured to the back forming members at the upper and lower edges of the latter, and a series of leaf-holding 65 wires slidably mounted in the guide members and extending longitudinally of the back-forming member.

8. A back and leaf binder comprising side 70 members each formed of superposed panels, spacing members interposed between the panels and forming transverse spaces between the latter opening at the longitudinal edges of the panels, a back-forming member 75 extending longitudinally between the side members and having lateral portions extending through said transverse spaces and connected at their outer ends to the inner panels, sleeves mounted on the inner panels adjacent the back-forming member, pins slidably 80 mounted in the sleeves and having hooks formed on their outer ends, hollow guide members extending transversely of the central part of the back forming member, collars fixed on the latter near the upper and 85 lower edges thereof supporting the guide members and a plurality of leaf-holding wires slidably mounted in the guide members, said guide-members having apertures 90 for the reception of said hooks.

In testimony that I claim the foregoing as my invention, I have signed my name.

MARCEL AIMON.
